WRAPPING DEVICE

Henry H. Wheeler, Bellerose, N. Y., assignor to
 International Cigar Machinery Company, a
 corporation of New Jersey

Application November 28, 1947, Serial No. 788,378

23 Claims. (Cl. 131—56)

1

This invention relates to cigar machines, more particularly to improvements in the wrapper applying device thereof which winds a wrapper cut from leaf tobacco about a cigar bunch spirally to produce a cigar.

Heretofore in wrapper applying devices of the type having a bottom roller and two side rollers the cigar bunch was supported with its longitudinal axis or center line in the same position regardless of variations in the diameter of the cigar bunch. Accordingly bottom rollers having different diameters were required to maintain the longitudinal axis of cigar bunches of various diameters in the same position. Therefore the position of the longitudinal axis of the bottom roller in these prior wrapper applying devices was different for different diameters of cigar bunches and different change gears were required to drive the side rollers with every change in the diameter of the cigar bunch to which the wrapper is applied.

With my improved wrapper applying device the diameter of the bottom roller is not changed and its longitudinal axis is always at the same position, because the bottom of cigar bunch is always maintained at the same position regardless of variations in the diameter thereof. Therefore the adjustment of the two side rollers to accommodate different diameters of cigar bunches does not necessitate different change gears to revolve the side rollers at the various positions to which they are adjusted to accommodate cigar bunches of different diameters. Accordingly, a further object of my invention is to provide a wrapper applying device whose side rollers may be driven in the various adjusted positions required for different diameters of cigar bunches without changing the gears driving the side rollers. Moreover my wrapper applying device can handle cigar bunches varying in diameter from $\frac{5}{8}$ inch to $\frac{7}{8}$ inch without changing the side rollers. For cigar bunches having diameters less than $\frac{5}{8}$ inch a different size of side roller is needed.

Still another object of the invention is to provide novel mechanism for supporting the side rollers which may be readily adjusted. In my construction the side rollers are supported in arms clamped on shafts supported in the housing, said shafts being turned to move the side rollers into closed position engaging the cigar bunch. With my construction upon unclamping said arms from the shafts the side rollers may be adjusted to conform to the diameter of the steel model cigars provided for the different sizes of cigars required, at the closed position of the rollers. With prior constructions the ends of the rollers are taper pinned in the brackets wherein they are supported, and a fixture must be used for this purpose. This taper pinning is a very fragile meth-

2

od of construction, and the rollers easily forced out of alignment, whereas my side rollers are supported much more rigidly by the arms mounted on the shafts supported by the housing. In this connection a further object of the invention is to provide a wrapper applying device which can be assembled more readily and in considerably less time than wrapper applying devices now used on cigar machines.

10 A still further object of the invention is to provide improved mechanism for driving the rollers at different speeds and thereby regulating the rolling speed of the cigar bunch to suit the stretching required for different types and conditions of the wrapper applied to the cigar bunch.

15 A further object is to provide a support for the bunch positioner which may be readily adjusted. For this purpose the bunch positioner is pivotally mounted on a split bracket which is clamped to a guide extending longitudinally of the housing. Upon unloosening the fastening connecting the separate sections of the bracket, the position of the bunch positioner may be adjusted to accommodate different lengths of cigar bunches.

20 25 A further object of this invention is to provide an improved mechanism for operating the tuck needle and locking it in the position wherein it holds the tuck end of the wrapper against the tuck end of the cigar bunch. In applying the tuck end of the wrapper to the cigar bunch the needle, which is normally in an upwardly inclined position, enters a notch in the bottom of the wrapper carrier on which the wrapper is suctionally retained in an outspread condition. The

30 35 needle is then depressed to strip said portion of the wrapper from the wrapper carrier and hold the same against the tuck end of the revolving cigar bunch to start the winding of the wrapper about the cigar bunch. Since the wrapper carrier will be in different positions for this operation, when different shapes of cigar bunches are being wrapped, the needle must have different positions to be inserted into the notch in the bottom of the wrapper carrier.

40 45 For this purpose the hollow bushing through which the needle projects has a narrow slot for guiding the needle, while it is being depressed, from the notch in the wrapper carrier to the tuck end of the cigar bunch. By adjusting my bushing circumferentially the position of the needle can be regulated to properly enter the notch in the bottom of the wrapper carrier at the different positions thereof required for different shapes of cigars.

50 55 An auxiliary object in connection with the mechanism for operating the tuck needle is to adjust this mechanism to suit the different levels at which the longitudinal axis of cigar bunches

of different diameters supported by the bottom roller may be located. For this purpose the bushing is mounted in a support which is vertically adjustable to align the depressed position of the needle with the longitudinal axis of cigar bunches of different diameters. Moreover the timing of the mechanism for depressing the needle may be varied to operate the needle at the proper time required for different shapes of cigars. With different shapes of cigars the wrapper carrier operating mechanism is designed to move the wrapper carrier to the position at which the tuck end of the wrapper is stripped from the carrier, while paste is being applied to its flag end, sooner or later in the cycle of operations. Adjustment of the timing of this mechanism, together with the vertical and circumferential adjustment of the bushing to align the needle with the different locations of the notch in the wrapper carrier bottom and the longitudinal axis of cigar bunches of different diameters, will cause the needle to properly enter the notch and apply the tuck end of the wrapper to cigar bunches of various sizes and shapes.

Other objects are to enclose the operating mechanisms for the various units of my wrapper applying device in a housing which supports the rollers on an exterior portion thereof. With my construction it is possible to operate the tension plate by mechanism of the general type shown in the Halstead Patent 1,582,597. With the construction shown in the Durning Patent 2,290,171 which shows a housing enclosing various units of a wrapper applying device, a more complicated type of mechanism for operating the tension plate is required.

A further specific object in this connection is to locate entirely within the housing the shaft on which is fulcrumed the cam lever supporting the header cone or disk so that paste dropping during the operation of the flag cutter or splitter will not drip on and foul said shaft. In a somewhat similar construction for operating the header cone or disk, which is shown in the Durning Patent 2,369,777, said cam lever is fulcrumed on a portion of said shaft which protrudes from the housing and is so located that the paste will drip on and foul it. Moreover with my construction a recess may be provided in one end wall of the housing to receive a paste can located to catch the dripping paste, whereas in prior constructions a paste chute was necessary to catch the dripping paste and deliver it to a paste receptacle.

A further object is to provide a device operated by the mechanism for separating the side rollers, for lifting the cigar off the bottom roller when the side rollers are separated to permit removal of the cigar bunch. If the cigar bunch were not lifted from the bottom roller during this operation, the rotation of the bottom roller would tend to displace the cigar transversely. Since the tuck end and head end of the cigar are supported on the tail block and header block respectively, the cigar will not be displaced but its wrapper might be injured by the rubbing of the bottom roller against it.

With these and other objects not specifically mentioned in view the invention consists in certain constructions and hereinafter fully described and set forth in the appended claims.

In the accompanying drawings which form a part of this specification:

Fig. 1 is a side elevation, partly in section of my improved cigar wrapping mechanism;

Fig. 2 is a plan view of the same;

Fig. 3 is an end elevation of the wrapping device as viewed from line 3—3 of Fig. 1, illustrating the tuck needle mechanism;

Fig. 4 is an end elevation taken from line 4—4 of Fig. 1, showing the flag cutter and header cone mechanism;

Fig. 5 is a sectional end elevation on an enlarged scale taken on line 5—5 of Fig. 1, illustrating the wrapping rollers in engagement with a cigar bunch;

Fig. 6 is a sectional end elevation taken on line 6—6 of Fig. 1 disclosing the wrapper roller speed change mechanism;

Fig. 7 is a sectional end elevation taken along line 7—7 of Fig. 1, illustrating the actuating means for the two upper wrapping rollers;

Fig. 8 is a sectional end elevation taken along line 8—8 of Fig. 1 showing the wrapper tension plate and its operating mechanism;

Fig. 9 is a sectional end elevation taken along line 9—9 of Fig. 1 depicting the cigar bunch positioning mechanism;

Fig. 10 is a detail end elevation of the bushing which supports the tuck needle; and

Fig. 11 is an enlarged view in perspective of the bushing 133 for the tuck needle.

Referring to the drawings which illustrate a cigar bunch wrapping mechanism exemplifying the invention and provided with a housing 12 carrying a horizontal cam or drive shaft 14 supported by suitable bearings located in the end walls of said housing. The cam shaft 14 is driven in a counter-clockwise direction indicated by the arrow in Fig. 6 in a suitable manner (not shown). The drive gear 18 (Figs. 1 and 6) which is secured to the shaft 14, meshes with the intermediate gears 20 and 22. A hub 24 is loosely mounted on the drive shaft 14. Screws 25 passing through elongated slots in the inner ends of arms 26 and 28 and threaded into hub 24 secure the arms 26 and 28 to hub 24. On the outer ends of arms 26 and 28 are revolubly mounted the intermediate gears 20 and 22. A shaft 30 mounted in housing 12 supports a pinion 32 engaging with either or neither of the intermediate gears or pinions 20 and 22, depending on the position of the speed control lever 33.

The speed control lever 33 is fixed to a shaft 34 which passes through and is supported by the end wall of the housing 12. This shaft 34 has an eccentric portion 36 on its inner end engaging a slot 38 of an arm 40 provided with a hub 42 which is integral with arm 40 and integral with the hub 24. Therefore, by manually positioning control lever 33 either gear 20 or 22 may be brought into mesh with the gear 32. Gear 22 is a wide faced gear having the same number of teeth at full width whereas gear 21, mounted side by side or made in one with gear 20, has one tooth less than gear 20. Since gear 21 has one tooth less than gear 20, a choice of speeds is possible which will be sufficient to regulate the rolling speed of the cigar bunch in a manner hereinafter described, to suit the stretching required on different grades and conditions of wrappers. The eccentric portion 36 of shaft 34 has a definite limited throw which is sufficient to disengage either gear 20 or 22 from gear 32 but is not sufficient if gear 32 is made considerably larger or smaller as is necessary for different models of cigars. Upon unloosening screws 25 the arms 26 and 28 may be adjusted upon hub 24 to cause both gears 20 and 22 to properly mesh

with and be disengaged from the various sizes of the gear 32 required for different models of cigars. Once set, however, the arms 26 and 28 remain in the same adjusted position so long as the same model of cigar is being manufactured.

A stop pin 43 projecting from the inner face of the end wall of housing 12 and passing through a hole in hub 42 engages either side of this hole when either the intermediate gear 20 or 22 meshes with the gear 32. The speed control lever 33 when against either of the limit pins 44 secured in the outer face of the end wall of housing 12 locks lever arm 40 through eccentric 36 against stop pin 43. When the lever 33 is midway between these limit pins 44, that is in a neutral position, neither gear 20 nor 22 will be meshed with gear 32. A pinion 46 on a shaft 50 supported in the end wall of housing 12, meshes with a spur gear 48 secured to and normally driven by the shaft 38 (Fig. 6). It is possible in the neutral position of lever 33 to turn the gear 48 and the wrapping rollers driven therefrom through a train of gears hereinafter described by a hand crank (not shown) engaging a slot 51 in the exterior end of shaft 50 (Fig. 3).

A stud 52 secured in the end wall of housing 12 supports a gear 54 which meshes with the spur gear 48 and drives a gear 56 secured on the bottom wrapping roller 58 mounted in suitable bearings in upwardly projecting lugs 12a and 12b formed on the end walls of the housing 12. The spur gear 56 meshes with the twin drive gears 60 and 62, loosely mounted on shafts 64 and 66 respectively which are also supported in bearings provided in the lugs 12a and 12b of housing 12. Gears 60 and 62 respectively drive pinions 68 and 70 fastened to the upper wrapping rollers 72 and 74.

A cigar bunch transfer of conventional construction (not shown) is provided to deposit the cigar bunch C upon the cradle 212 after the two upper wrapper rollers 72 and 74 are swung into open position by the mechanism illustrated in Fig. 7. This mechanism includes a cam follower 80 mounted on a shaft 81 slidably mounted in a bushing 82 in the top of housing 12. A compression spring 83 mounted in a bore in the upper end of shaft 81 and seated against a bar 84 secured to lugs 85 on the top of housing 12 urges the cam follower against the cam lobe 86a of a cam 86 secured on shaft 14. The upper end of shaft 81 is connected by the links 87 to arms 89, 98 clamped on shafts 64 and 66. Arms 90, which are also clamped on shafts 64 and 66 by screws 91 connecting the split ends thereof, support the ends of rollers 72 and 74. Arms 89 are substantially the same as arms 90 as may be seen in Fig. 1. In end elevation they appear the same as arms 90 as shown in Fig. 7. When the cam lobe 86a of cam 86 engages the cam follower 80 the rollers 72 and 74 are swung into their open position. When the cam follower 80 leaves cam lobe 86a the upper rollers 72 and 74 are swung in the direction indicated by the arrows in Fig. 7 to engage the sides of the cigar bunch C. The inward movement of rollers 72 and 74 is limited by their engagement with the sides of the cigar bunch C. Therefore various sizes of cigar bunches will be accommodated between the rollers 72 and 74, since the cam follower 80 does not engage the cam 86 after leaving the cam lobe 86a so that the rollers 72 and 74 are held against the cigar bunch by the pressure of spring 83. The arms 89, 90 may be adjusted on shafts 64 and 66 after the screws 91 are loosened, and 75 During the outward movement of the upper end

while cam follower is off cam lobe 86a, to engage the sides of the various steel model cigars positioned on bottom roller 56 corresponding to the cigar bunches to be wrapped. Screws 91 are then tightened and the cigar bunch may then be wrapped.

A graduated dial 92 secured on shaft 14 and a pointer 94 secured to housing 12 are provided to permit the accurate adjustment of the timing of the mechanism for operating the tuck needle which will be hereinafter fully described.

In Figs. 2, 4 and 8 is shown the tension plate mechanism which is generally similar in construction to that shown in the Halstead Patent

15 1,582,597. My tension plate mechanism is provided with a bracket 100 pivotally mounted on a non-rotatable shaft 102 mounted on an exterior portion of the housing 12. On a shaft 103 supported at the upper end of the bracket 100 are 20 pivotally mounted the lugs 104 and 105 of a support 106. A tension plate 108 secured to support 106 is urged upwardly by a torsion spring 110 located in lug 105 and having one of its ends anchored therein and its other end anchored 25 in a collar 112 secured to one end of shaft 103. A roller 113 mounted on an extension 114 of lug 104 rides on a cam surface 115 formed on the upper end of an arm 116 which is pivoted on a stud 117 secured in an arm 118 fastened on shaft 30 102. A torsion spring 119 (Fig. 2) whose ends are connected respectively to the stud 117 and the hub of arm 116 normally maintains the latter in a position wherein the inner end of cam surface 115 underlies roller 113. Bracket 100 is urged inwardly by a compression spring 120 seated in a socket in housing 12 and engaging a lug 121 on the lower end of bracket 100. One arm of a bell crank lever 122 pivoted on shaft 102 engages a stop-screw 124 threaded into bracket 100. The other arm of bell crank lever 122 extends through a slot 125 (Figs. 1 and 8) in housing 12 and carries a cam follower 126 which engages the periphery of a cam 127. Cam 127 has adjustable cam sections 128 and 130 which are mounted on shaft 14, and cam follower 126 is held in engagement therewith by a tension spring 132. It will be noted that cam 127 is located within housing 12 and serves to operate the tension plate mechanism.

40 50 An adjustable stop-screw 134 threaded into bracket 100 and arranged to engage housing 12 limits the extent to which the bracket 100 may be urged inwardly by spring 120 during the rotation of cam 127. A link 136 pivotally connected 55 to the upper end of lever 122 has an elongated slot 137 (Fig. 8) engaging a stud 138 on link 116. During the inward movement of the upper end of lever 122 the outer end of slot 137 engages the stud 138 whereby arm 116 is swung inwardly 60 with bracket 100. Therefore the roller 113 rides on the inner end of cam surface 115 until the stop-screw 134 on bracket 100 during the inward movement of the latter engages the housing 12 as shown in Fig. 8. The continued inward movement of the arm 116 due to the displacement of link 136 by bell crank 122 moves the arm 116 relative to bracket 100. The outer end of cam surface 115 is thereby moved underneath roller 113 and the support 106 is swung upwardly to allow 65 the tension plate 108 to guide the wrapper, which is suctionally held on the bottom of a wrapper carrier (not shown), while said wrapper is being removed from the carrier by the rotation of the cigar bunch C and wound about the cigar bunch. 70 75 During the outward movement of the upper end

of lever 122 the outer end of slot 136 engages the stop-screw 139 on arm 116 and displaces the latter outwardly relative to bracket 100 to permit the inner end of cam surface 115 to reengage roller 113 and thereby swing support 106 downwardly with tension plate 108. The upper end of lever 122 reengages the stop-screw 124 and swings the bracket 100 outwardly to its initial position while the link 116 continues its outward movement.

A header block 140 (Figs. 1, 2 and 4), which is of conventional construction, such as disclosed in the Halstead Patent Re. 20,355, has a concave face fitting the head end of the cigar bunch C deposited on the bottom wrapping roller 58 between the upper rollers 72 and 74. The header block 140 is secured in the lug 12a of the housing 12. The tail block or tuck support 141 (Figs. 1 and 2) is secured to the upper end of a split bracket 164 hereinafter described, through which the bottom roller 58 projects. Tail block 141 has a concave face fitting the tuck end of the cigar bunch C.

In Figs. 1, 2 and 9 there is shown a bunch positioner mechanism operated by a cam 142 secured on shaft 14 and acting on a cam roller 143 supported on the inner end of a cam lever 144 which projects through a slot 145 in housing 12 and is fulcrumed on shaft 102. A torsion spring 146 having its ends anchored in the hub of lever 144 and a collar 147 secured on shaft 102 keeps the roller 143 in contact with the periphery of the cam 142. A vertical shaft 148 is connected to the cam lever 144 by a block 150 pivoted on lever 144 and having a bifurcated portion into which the lower end of shaft 148 extends. A pin 152 pivotally connects the bifurcated portion of block 150 to shaft 148, a cotter pin 154 passing through the projecting end of pin 152. On the upper end of shaft 148 is provided a horizontal U-shaped channel member 156. A bunch positioner arm 158, which has an elongated operating face 158a, is pivoted on a shaft 160 supported in bracket 164. Shaft 160 has a projecting portion provided with a finger 162 riding in the channel of member 156 and thereby turning the shaft 160 as a result of the vertical movement of shaft 148. Thus the operating face 158a of arm 158 will engage with the tuck end of the cigar bunch C to position the same longitudinally in the required position after it has been deposited upon the cradle 212 with its ends supported on the header block 140 and the tail block 141. The sections of the split bracket 164 are held together by a screw 165 and thereby secured to a T plate 166 fastened to the top of housing 12. Upon unloosening the screw 165 the bracket 164 may be adjusted to accommodate different lengths of cigar bunches. It may be noted that with the horizontal arrangement of my screw 165 it is much more accessible than the vertical fastenings of prior constructions for supporting the bunch positioner.

In the cycle of operations for wrapping a cigar bunch the wrapper to be applied to the bunch is brought to a position directly above the wrapping rollers by a wrapper carrier (not shown). In order to remove the tuck end of the wrapper from the wrapper carrier and apply it to the bunch, a cam operated tuck needle 167 is supported by a bifurcated member 168 pivoted on a horizontal shaft 170 supported in lugs 172 of the housing 12. A torsion spring 174, whose outer end is anchored in a collar 175 secured on shaft 170, urges the bifurcated member 168 to a

retracted position. Adjustably mounted on the free end of the arm 168 is a plate 176 which is slotted to provide arms extending on either side of tuck needle 167 in the space between the adjustable stop 178 and the adjustable guide 180 which are secured on the tuck needle. An annular cam 182 is mounted on a hub 183 keyed to the end of the drive shaft 14 projecting from the housing 12. Cam 182 is provided with a cam track engaging the cam roller 184 mounted on arm 185 of member 168 to rock the arm 168 forwardly against the resistance of spring 174 and thereby move the tuck needle 167 forwardly through a hollow bushing 188 wherein the inner end of the needle is supported. Needle 167 is normally maintained in an upwardly inclined position by a counterweight 191 (Fig. 3) on the outer end thereof against the upper end of slot 188b in bushing 188. Bushing 188 is supported in the cover bracket 190 and has a conical recess 188a in its outer end and a slot 188b extending from the apex of the recess 188a to the inner end of the bushing, through which the needle 167 projects. The slot 188b has a predetermined shape shown in Fig. 10 to guide the needle, when it is depressed from its normal upwardly inclined position, from the notch in the bottom of the wrapper carrier to the tuck end of the cigar bunch C, whereby the flexible tip 192 of the needle will apply the tuck end portion of the wrapper to the tuck end of the cigar bunch.

The cover bracket 190 is secured to the lug 12b of housing 12 by screws 193 passing through elongated slots 194 of bracket 190 and threaded into said lug 12b. Bracket 190 is provided with a vertical channel 189 extending along its inner face upwardly from its lower end, as shown in Fig. 1, and terminating adjacent the upper end of the bracket 190. A vertical slide 195 is slidably mounted in channel 189. A compression spring 197 interposed between the upper end of channel 189 and the upper end of slide 195 maintains a cam roller 196 supported on the lower end of slide 195 in position to engage with the lobe 197a of a cam track 197 formed on cam 182. Cam 197 has an annular construction and is integral with cam 182. A member 198 secured to slide 195 by a screw 199 (Fig. 1) projects upwardly beyond the upper end of bracket 190. Needle 167 projects through a vertical slot 198a formed in the upper end of member 198.

After the tip 192 of the needle has been inserted into the notch in the tuck portion of the bottom of the wrapper carrier (not shown) during the forward motion of member 168, the attached plate 176 bears against the base of guide 180 to move it into contact with conical recess 188a in bushing 188. In this position, the flat base of guide 180 is in angular contact with plate 176, the plate contacting the top portion thereof. Further movement of plate 176 results in tilting guide 180 with the needle into a horizontal position, since the now vertical plate 176 will bear solidly against the flat base of guide 180. The cam follower 196 then rides off the cam lobe 197a of cam 197, and the slide 195 moves downwardly and thereby locks the needle in its horizontal depressed position. The tuck end portion of the wrapper is thus stripped from the wrapper carrier, whereon the wrapper is suctionally retained, and held against and wound about the tuck end of the cigar bunch C while the latter is revolved by rollers 58, 72 and 74 approximately $1\frac{1}{4}$ revolutions. The needle is then withdrawn horizontally by the engagement of plate 176 on

the member 168 with the collar 178 on the needle. The wrapper is guided and held against the bottom of the wrapper carrier by the tension plate 166 to maintain the proper tension of the wrapper while the remainder thereof is spirally wound about the cigar bunch C. Reference may be had to my prior Patent 2,235,857 and the Halstead Patent 2,376,355 for a suitable construction of the wrapper carrier (not shown) and suitable mechanism for moving the wrapper carrier in a predetermined path while the wrapper is spirally wound about the cigar bunch C.

Mechanism is provided to permit adjustment of the timing of the operation of the tuck needle whereby the needle may be inserted into the notch in the carrier at the various positions thereof required for different models of cigars. For this purpose a pinion 200 (Fig. 3) has a shank revolvably mounted in a semi-cylindrical bore in the interior face of cam 182 (Fig. 3). Pinion 200 meshes with an external gear 201 formed on the periphery of the hub 183 of cam 182. By inserting a screw-driver in the slot in the outer end of pinion 200 and turning the latter the cam 182 may be turned relatively to the hub 183. The operation of member 168 will be advanced or retarded and the needle 167 will be depressed and locked sooner or later in the cycle or operations. The shank of pinion 200 may then be locked by a set screw 200a threaded into the cam 182.

The notch in the bottom of the wrapper carrier will be adjusted to be in different positions for different models of cigars. Therefore, the needle 167 must be adjusted to enter said notch at the various locations thereof required for different models of cigars. For this purpose the bushing 188 is circumferentially adjustable in the bracket 190 to cause the top of the slot 188b thereof to displace the needle transversely to the position required to enter the notch in the wrapper carrier bottom. This adjustment never exceeds a few degrees, since a slight movement at this point is greatly exaggerated at the needle tip 192 and is sufficient for all standard sizes of cigars. It may be noted that the lower end of slot 188b is at the center of the bushing and accordingly in the various adjusted positions of bushing 188 coincides with the horizontal depressed position of the needle. Therefore, the needle in being depressed from the various transversely adjusted positions thereof will apply the tuck end portion of the wrapper to the same portion of the tuck end of the cigar bunch. When the needle 167 is in the lower end of the slot 188b it is concentric with bushing 188 and hence its depressed position is unaffected by the adjustment of the bushing. After the bushing 188 is circumferentially adjusted it is locked in position in bracket 190 by a set screw (not shown).

Upon unloosening the screws 193 securing the bracket 190 to the lug 12b of housing 12, the bracket 190 may be moved vertically to adjust the bushing 188 vertically to align the horizontal depressed position of the tuck needle with the longitudinal axis of the cigar bunch. The spring 187 urges the slide bar 195 and its cam roller 196 downwardly. A needle locking member 198 secured to slide bar 195 locks the needle against the bore of bushing slot 188b when the slide bar is in lowered position. The lobe 197a of the cam 197 has sufficient stroke to lift the locking plate 198 by means of the cam roller 196 and bar 195 to release the needle at the highest possible adjusted position of the bushing 188. This adjust-

ment is necessary when cigar bunches of different diameters are to be handled, since the bottom of the wrapper carrier will be higher or lower in accordance with differences in the diameter of the cigar bunch to be wrapped. This adjustment will permit the tuck needle 167 to strip the tuck end portion of the wrapper from the wrapper carrier and apply it to the tuck end of cigar bunches of various diameters.

When all but the flag end of the wrapper is removed from the wrapper carrier, the flag end of the wrapper to which paste was previously applied by suitable mechanism (not shown), such as illustrated in Shedlock Patent 863,106, is blown down from the wrapper carrier by suitable mechanism such as shown in the Carlson Patent 2,292,361. The paste on the flag end of the wrapper causes it to adhere to the tension plate 166 and the lug 168a of the latter, as the flag end is drawn over the tension plate after being blown down from the wrapper carrier.

The construction of the flag cutter is similar to that shown in the Durning Patent 2,369,777. My flag cutter includes a stationary knife blade 202 secured to one end of a bracket 204 which corresponds to the bracket 117 of Durning Patent 2,369,777. The other end of my bracket 204 is secured on a sleeve 206 clamped in the outer end of an arm 208 pivoted on a stub shaft 210 mounted in the lug 12a of housing 12. On the inner end of a shaft 213 revolvably mounted in sleeve 206 is secured the hub of a double-blade knife 214. On the outer end of shaft 213 is secured a driven member 216 which is normally out of engagement with a driving member or pulley 218. Driving member 218 is driven from another unit of the cigar machine (not shown) by an elastic belt 219. Driving member 218 is mounted on a shaft 220 supported by an arm 222 mounted on one end of a shaft 224 supported by housing 12.

The mechanism for raising the arm 222 to cause the pulley 218 to engage and drive member 216, and thereby revolve the knife 214 to slit the flag end of the wrapper, is unlike the corresponding mechanism shown in the Durning Patent 2,369,777 in that my cam lever 226 is not bifurcated. Cam lever 226 is mounted on the other end of shaft 224 and carries a cam roller 227 engaging a cam 228 secured on shaft 14. The cam 228 has a predetermined configuration to maintain the pulley 218 in a lowered position out of engagement with member 216 on the shaft 213 carrying the knife 214. Although cam lever 226 is not bifurcated (unlike the corresponding cam lever 129 of the Durning Patent 2,369,777) my finger 230 (corresponding to the finger 128 of said Durning Patent) is pivoted on the lever 226. A tension spring 232, which is connected to posts on the finger 230 and lever 226, maintains the finger 230 in operative position. A cam 234 mounted on shaft 14 at one side of cam 228 has a predetermined configuration to engage and lift finger 230 and thereby raise pulley 218 into engagement with member 216 to effect the cutting of the flag end of the wrapper. During this operation the cam roller 227 is lifted off cam 228. When finger 230 drops off the lobe 234a of cam 234 the pulley 218 is disengaged from the driven member 216 and a stop screw 236 on arm 222 drops into engagement with a pin 238 secured in housing 12. Since the construction of my cam 234 is similar to the corresponding cam 122 of the above-mentioned Durning Patent 2,369,777, further description thereof is deemed unnecessary. It may be noted that the reengagement of cam

228 with cam roller 227 lifts the stop screw 236 off pin 238.

A header cone 250 secured in the free end of an arm 252 serves in its operative position to apply the flag end of the wrapper after it is slit by knives 202 and 214 to the head end of the cigar bunch. The other end of arm 252 is connected to a cam lever 254 which is mounted on a shaft 256 secured in housing 12 at an inclination to the axis of the cigar bunch C. Lever 254 has an arm 258 which is normally held in engagement with the free end of cam lever 226 by a torsion spring 260 mounted on shaft 256 and having its ends anchored in the hub of lever 254 and a collar 262 secured on shaft 256. The header cone 250 is thereby maintained out of operative position until the finger 230 rides off the cam lobe 234a of cam 234 and thereby disengages the cam lever 226 from the arm 258 of the lever 254. Thus the torsion spring 260 will swing the lever 254 upwardly and press the header cone 250 against the slit flag end of the wrapper. The flag end of the wrapper will be applied to head end of the cigar bunch C. The header cone will thus serve to press and smooth and thereby finish the application of the wrapper to the cigar bunch C.

It will be noted that the shaft 256 is mounted within the housing 12. Therefore, when the shaft 256 is covered by a removable section (not shown) of housing 12, it will not be fouled by excess paste dripping from the flag end of the wrapper.

In the operation of my wrapper applying device the tuck end of a wrapper W (Fig. 5) is stripped from a wrapper carrier (not shown) and wound about the tuck end of the cigar bunch C by the tuck needle 167. The remainder of the wrapper is guided over the tension plate 108 while being wound about the cigar bunch by the rotation thereof produced by rollers 58, 72 and 74 until the flag end of the wrapper is blown down from the wrapper carrier upon the tension plate. The flag end of the wrapper is then slit by the coaction of the knives 202 and 214 and applied to the head end of the bunch by the header disk 250 to form a cigar.

The side rollers 72 and 74 are then moved outwardly away from the cigar. The cigar is now lifted off the bottom roller 58 by mechanism, which will now be described, into position to be picked up by the cigar transfer (not shown) and removed. A pair of U-shaped lift bars 212 (Figs. 1 and 5) have bifurcated ends 211 engaging circumferential slots in eccentric collars 214 clamped to shafts 64 and 66 by screws 215 passing through the split portions of collars 214. Thus the bars 212 will be raised and their ends will lift the cigar off the roller 58 when the shafts 64 and 66 are turned to disengage the upper wrapping rollers 72 and 74 from the sides of the cigar to permit easy grasping and removal thereof by the cigar transfer (not shown). The position of collars 214 upon shafts 64 and 66 may be regulated after unloosening the screws 215, to regulate the distance the cigar is lifted by bars 214.

What is claimed is:

1. In a device for applying a wrapper to a cigar bunch, the combination with a revoluble bottom roller adapted to support a cigar bunch, of a pair of revoluble side rollers adapted to engage the sides of said cigar bunch, mechanism for moving said side rollers into engagement with the sides of a cigar bunch supported on said bottom roller, means for simultaneously driving said bottom

and side rollers to revolve said cigar bunch, said mechanism including a rocker shaft, arms adjustably mounted on and about said shaft and supporting said side rollers at each end thereof and being adjustable to vary the positions of said side rollers along their length at their ends on and about said shaft permitting the accommodation of cigar bunches of various diameters between said side rollers without changing the diameter of said bottom roller, and said roller driving means operating to drive said side rollers in the various adjusted positions thereof.

2. In a device for applying a wrapper to a cigar bunch, the combination with a support, of a horizontal bottom roller revolvably mounted in said support and adapted to support a cigar bunch about which a wrapper is to be spirally wound, a pair of shafts revolvably mounted in said support, a plurality of arms adjustably mounted on and about each of said shafts, a pair of opposed horizontal side rollers revolvably mounted in each of said arms and adapted to engage the sides of a cigar bunch supported on said bottom roller, said arms being adjustable on and about said shafts permitting the accommodation of cigar bunches of various diameters between said side rollers, means for turning said shafts to move said side rollers into engagement with the sides of a cigar bunch, and mechanism for simultaneously driving said bottom roller and side rollers to revolve said cigar bunch during the application of the wrapper thereto while said side rollers engage the sides of said cigar bunch.

3. In a three roll device for applying a wrapper to a cigar bunch, the combination with a revoluble bottom roller adapted to support a cigar bunch about which a wrapper is to be spirally wound, of a pair of revoluble side rollers adapted to engage the sides of said cigar bunch, mechanism for moving said side rollers into engagement with the sides of a cigar bunch supported on said bottom roller to wind a wrapper spirally on said cigar bunch, means for simultaneously driving said bottom and side rollers to revolve said cigar bunch while the wrapper is being wound spirally thereon, said mechanism being adjustable to vary the positions of said side rollers relative to each other to accommodate cigar bunches of various diameters between said side rollers without changing the diameter of said bottom roller, and said roller driving means operating to drive said side rollers in the various adjusted positions thereof, said mechanism including a shaft, supports adjustably pivoted to said shaft and supporting said side rollers, a vertically reciprocable member connected to said shaft to oscillate it, a rotary cam, a cam follower on said member, the periphery of said cam having a predetermined configuration to engage said cam follower and thereby displace said member to oscillate said shaft to move said side rollers out of engagement with said cigar bunch, and a spring coacting with said member to move said side rollers into engagement with said cigar bunch.

4. In a device for applying a wrapper to a cigar bunch, the combination with a series of rollers coacting to support and revolve a cigar bunch about which a wrapper is to be spirally wound, of means for driving said rollers to revolve said cigar bunch while the wrapper is being spirally wound thereon, said roller driving means including a drive shaft, a drive gear mounted on and driven by said shaft, a hub mounted on said shaft, a pair of broad faced pinions mounted on said support

and driven by said drive gear, one of said pinions having a differential number of gear teeth at one end to provide a speed change, a gear train adapted to be driven from one end of either of said pinions and operating to drive said rollers to revolve said cigar bunch, said hub having an arm, said arm having an opening extending radially thereof a rotatable eccentric engaging said opening for turning said hub a predetermined distance in either direction relatively to said shaft to engage or disengage either of said pinions with said gear train and thereby drive said rollers at either of two different speeds and an operating lever to turn said eccentric in said opening.

5. In a device for applying a wrapper to a cigar bunch, the combination with a hollow bushing, of a tuck needle projecting through said bushing and adapted to apply the tuck end of a wrapper to a revolving cigar bunch, means for supporting said needle in an upwardly inclined position and moving it forwardly through said bushing into a predetermined position wherein it overlies the tuck end portion of a wrapper which is to be applied to said cigar bunch and then depressing said needle into a horizontal position to apply the tuck end of said wrapper to said cigar bunch, and a vertically adjustable support on which said bushing is mounted whereby adjustment of said support will raise or lower said bushing with said needle to permit application of the wrapper to cigar bunches of various diameters.

6. In a device for applying a wrapper to a cigar bunch, the combination with a hollow bushing, of a tuck needle projecting through said bushing and adapted to apply the tuck end of a wrapper to a revolving cigar bunch, means for supporting said needle in an upwardly inclined position and moving it forwardly through said bushing into a predetermined position wherein it overlies the tuck end portion of a wrapper which is to be applied to said cigar bunch and then depressing said needle into a horizontal position to apply the tuck end of said wrapper to said cigar bunch, and a vertically adjustable support on which said bushing is mounted whereby adjustment of said support will raise or lower said bushing with said needle to permit application of the wrapper to cigar bunches of various diameters, and mechanism for locking said needle in its depressed position at the various adjusted positions of said support.

7. In a device for applying a wrapper to a cigar bunch, the combination with a hollow bushing, of a tuck needle projecting through said bushing and adapted to apply the tuck end of a wrapper to a revolving cigar bunch, means for supporting said needle in an upwardly inclined position and moving it forwardly through said bushing into a predetermined position wherein it overlies the tuck end portion of a wrapper which is to be applied to said cigar bunch and then depressing said needle into a horizontal position to apply the tuck end of said wrapper to said cigar bunch, and a vertically adjustable support on which said bushing is mounted whereby adjustment of said support will raise or lower said bushing with said needle to permit application of the wrapper to cigar bunches of various diameters, and mechanism for locking said needle in its depressed position at the various adjusted positions of said support, said needle locking mechanism including a vertically movable member slidably mounted on said support, said member having an elongated slot through which said needle projects, a cam follower connected to said member, a cam adapted to engage said cam follower to move said member

upwardly into an ineffective position at the various adjusted positions of said support, and a spring coacting with said member to move the latter downwardly and thereby lock said needle in depressed position at the various adjusted positions of said support.

8. In a device for applying a wrapper to a cigar bunch, the combination with a hollow bushing, of a tuck needle projecting through said bushing and adapted to apply the tuck end of a wrapper to a revolving cigar bunch, means for supporting said needle in an upwardly inclined position and moving it forwardly through said bushing into a predetermined position wherein it overlies the tuck end portion of a wrapper which is to be applied to said cigar bunch and then depressing said needle into a horizontal position to apply the tuck end of said wrapper to said cigar bunch, and a support on which said bushing is mounted, said bushing having a vertical slot through which said needle projects and said slot being adapted to guide the needle into position to apply the tuck end of the wrapper to the tuck end of the cigar bunch while the needle is being depressed by said means, said bushing being circumferentially adjustable in said support to vary the position into which said needle is moved by said means without varying the position into which said needle is depressed by said means.

9. In a device for applying a wrapper to a cigar bunch, the combination with a revolute bottom roller adapted to support a cigar bunch about which a wrapper is to be spirally wound, of a pair of revolute top rollers adapted to engage the sides of said cigar bunch, mechanism for moving said top rollers into engagement with the sides of a cigar bunch supported on said bottom roller, to wind a wrapper spirally on said cigar bunch, means for simultaneously driving said bottom and top rollers to revolve said cigar bunch while the wrapper is being wound spirally thereon, said mechanism being adjustable to vary the positions of said top rollers relative to said bottom roller to accommodate cigar bunches of various diameters between said top rollers without changing the diameter of said bottom roller, and said roller driving means operating to drive said side rollers in the various adjusted positions thereof, a hollow bushing, a tuck needle projecting through said bushing and adapted to apply the tuck end of said wrapper to said cigar bunch, means for supporting said needle in an upwardly inclined position and moving it forwardly into a predetermined position wherein it overlies the tuck end portion of a wrapper which is to be applied to said cigar bunch and then depressing said needle to cause it to apply said wrapper portion to said cigar bunch, and a vertically adjustable support on which said bushing is mounted whereby adjustment of said support will raise or lower said bushing with said needle to permit application of the wrapper to cigar bunches of various diameters.

10. In a device for applying a wrapper to a cigar bunch, the combination with a slotted bushing having a substantially vertical slot extending substantially upwardly from the center thereof, of a tuck needle projecting through said slot and adapted to apply the tuck end of a wrapper to a revolving cigar bunch, means for supporting said needle in an upwardly inclined position and moving it forwardly through the upper end of said slot into a predetermined position wherein it overlies the tuck end portion of a wrapper which is to be applied to said cigar bunch and then depressing said needle into a horizontal position to apply the tuck end of said wrapper to said cigar

bunch, and a support on which said bushing is mounted, said means including a movable member adapted to move said needle forwardly through said bushing into said predetermined position, a cam follower connected to said member, a drive shaft, a cam on said drive shaft engaging said cam follower to operate said member, and a device for turning said cam relatively to said shaft to vary the time at which said needle is moved forwardly into said predetermined position.

11. In a device for applying a wrapper to a cigar bunch, the combination with a slotted bushing having a substantially vertical slot extending substantially upwardly from the center thereof, of a tuck needle projecting through said bushing and adapted to apply the tuck end of a wrapper to a revolving cigar bunch, means for supporting said needle in an upwardly inclined position and moving it forwardly through said bushing into a predetermined position wherein it overlies the tuck end portion of a wrapper which is to be applied to said cigar bunch and then depressing said needle into a horizontal position to apply the tuck end of said wrapper to said cigar bunch, and a support on which said bushing is mounted, said means including a device for adjusting the upward inclination of said needle, and a movable member arranged in close proximity to said bushing and adapted to engage a portion of said needle adjacent said bushing at the various upwardly inclined positions thereof obtained with said adjusting device and lock said needle in the depressed position.

12. In a device for applying a wrapper to a cigar bunch, the combination with a slotted bushing, of a support on which said bushing is mounted, a tuck needle projecting through said bushing and adapted to apply the tuck end of a wrapper to a revolving cigar bunch, means for supporting said needle in an upwardly inclined position and moving it forwardly through said bushing into a predetermined position wherein it overlies the tuck end portion of a wrapper which is to be applied to said cigar bunch and further means for then depressing said needle into a horizontal position to apply the tuck end of said wrapper to said cigar bunch, said further means including a device for transversely adjusting the portion of said needle projecting from said bushing to cause the tip of the needle to be advanced into various predetermined positions, and a movable member arranged in close proximity to said bushing and adapted to engage and lock said needle in its depressed position at the various transversely adjusted positions thereof.

13. In a device for applying a wrapper to a cigar bunch, the combination with a hollow bushing, of a support on which said bushing is mounted, a tuck needle projecting through said bushing, means for depressing said needle from an upwardly inclined position into a horizontal position, and a movable member arranged to engage the top of said needle and lock it in depressed position.

14. In a device for applying a wrapper to a cigar bunch, the combination with a hollow bushing, of a tuck needle projecting through said bushing and adapted to apply the tuck end of a wrapper to a revolving cigar bunch, means for supporting said needle in an upwardly inclined position and moving it forwardly through said bushing into a predetermined position wherein it overlies the tuck end portion of a wrapper which is to be applied to said cigar bunch and

then depressing said needle into a horizontal position to apply the tuck end of said wrapper to said cigar bunch, and a support and mechanism for locking said needle in its depressed position, 5 said needle locking mechanism including a vertically movable member, slidably mounted on said support, said member having an elongated slot through which said needle projects, a cam follower connected to said member and a cam co-acting with said cam follower and operating said member.

15. The combination with a support, of a hollow bushing mounted in said support and adapted to support in an upwardly inclined position a tuck needle projecting through said bushing, said bushing having a portion adapted to displace said needle transversely to a predetermined position while it is being depressed from an upwardly inclined position to a horizontal position, and said bushing being circumferentially adjustable in said support to cause said portion of said bushing to displace the needle transversely to various upwardly inclined positions and guide said needle from said various upwardly inclined positions to the same predetermined horizontal position while the needle is depressed to the horizontal position.

16. In a three roll device for applying a wrapper to a cigar bunch, the combination with a revoluble bottom roller adapted to support a cigar, 30 of a U-shaped cradle mounted about said bottom roller for movement transverse thereto and having a portion adapted to lift the cigar bunch from said bottom roller; of a pair of revoluble side rollers adapted to engage the sides of said cigar bunch, mechanism for moving said side rollers into and out of engagement with the sides of a cigar bunch supported on said bottom roller said mechanism consisting of rocker shafts, arms 35 secured to said shafts and supporting said rollers on and about said shafts, and movable members secured to said shafts engaging and supporting said cradle about said bottom roller to lift said cradle with said cigar bunch when said rocker shaft is oscillated and the side rollers are moved thereby out of engagement with the sides of the cigar bunch and to lower the cradle when said side rollers are moved into engagement with the sides of the cigar bunch.

17. In a device for applying a wrapper to a cigar bunch, the combination with a revoluble bottom roller and then moving said side rollers 40 pair of revoluble side rollers adapted to engage the sides of said cigar bunch, mechanism for moving said side rollers into engagement with the sides of a cigar bunch supported on said bottom roller and then moving said side rollers away from the sides of said cigar bunch to permit removal thereof, and a device operated by said mechanism for lifting said cigar bunch from said bottom roller when said side rollers are moved away from the sides of the cigar bunch, said mechanism including a pair of revoluble shafts and supports for said side rollers pivoted 45 on said shafts, and said device including eccentric collars secured on said shafts and a cradle having bifurcated portions engaging said eccentric collars and adapted to engage and lift the cigar bunch off the bottom roller when said shafts are turned to disengage said side rollers from the sides of the cigar bunch.

18. In a device for applying a wrapper to a cigar bunch, the combination with a series of rollers co-acting to support and revolve a cigar bunch about which the wrapper is to be spirally

wound, means for driving said rollers to revolve said cigar bunch while the wrapper is being spirally wound thereon, said roller driving means including a drive shaft, a drive gear mounted on and driven by said shaft, a support mounted on said shaft, said support including a sleeve on said shaft, a pair of arms secured to said support, a pair of pinions mounted on said arms and driven by said drive gear, one of said pinions having a different number of gear teeth than the other pinion for engaging said driven gear to provide a different gear ratio than said other pinion, a gear train adapted to drive said rollers to revolve said cigar bunch, said gear train including a driven gear arranged to be driven from either of said pinions, a third arm integral with said support, an opening in said arm, a rotatable eccentric engaging said opening to turn said support in either direction relative to said shaft to engage or disengage either of said pinions from said gear train, and stop means to resist the action of said eccentric at the limit of its throw to effect locking engagement therewith whereby said support is locked when either of said pinions is in engagement with said driven gear.

19. In a device for applying a wrapper to a cigar bunch, the combination with a series of rollers co-acting to support and revolve a cigar bunch about which the wrapper is to be spirally wound, means for driving said rollers to revolve said cigar bunch while the wrapper is being spirally wound thereon, said roller driving means including a drive shaft, a drive gear mounted on and driven by said shaft, a gear train adapted to drive said rollers to revolve said cigar bunch, said gear train including a primary or driven gear, a device loosely mounted on said shaft for guiding said gear train to said primary driven gear, said device including a support on said shaft, a pair of arms each, separately adjustably secured to said support and extending radially thereof, each of said arms being adjustable on said support relative to each other, a pair of pinions mounted on said arms and driven by said drive gear, one of said pinions having a different gear ratio than the other pinion whereby on rotation of said sleeve one of said pinions will engage said primary driven gear, a plate secured to said support, said plate having a radial member, a radial slot in said member, a rotatable eccentric engaging said slot for moving said plate in either direction relative to said shaft, and stop means to limit the movement of said plate in either direction at the limit of throw of said eccentric to resist the action of said eccentric to effect locking engagement therewith.

20. In a device for applying a wrapper to a cigar bunch, the combination with a series of rollers coacting to support and revolve a cigar bunch about which the wrapper is to be spirally wound, means for driving said rollers to revolve said cigar bunch while the wrapper is being spirally wound thereon, said roller driving means including a drive shaft, a drive gear mounted on and driven by said shaft, a support mounted on said shaft, said support including a hub, a pair of angularly spaced arms mounted on said hub, a pair of pinions mounted on said arms and driven by said drive gear, a gear train adapted to drive said rollers to revolve said cigar bunch, said gear train including a driven gear arranged to be driven from either of said pinions, one of said pinions having a different number of gear teeth than the other pinion for engaging said driven

gear to provide a different gear ratio than said other pinion, a device for oscillating said hub a predetermined distance in either direction relative to said shaft to engage or disengage either of said pinions with said gear train and thereby drive said rollers at either of two different speeds, and means to adjust said arms relative to said hub to accommodate different sizes of said driven gear so that the amount of mesh between said driven gear and said pinion is established by said predetermined distance through which said hub is oscillated.

21. In an apparatus for applying a wrapper to a cigar bunch, the combination with a hollow bushing, of a support for said bushing, a tuck needle projecting through said bushing and adapted to apply the tuck end of a wrapper to a revolving cigar bunch, means for supporting said needle in an upwardly inclined position and moving it forwardly through said bushing into a predetermined position and then depressing said needle into a horizontal position, and a slideable element arranged in close proximity to the position of the needle supported in said bushing for engaging the needle and engaging the top of and varying the upper position of said needle.

22. In an apparatus for applying a wrapper to a cigar bunch, a bearing, a hollow rotatably adjustable bushing within said bearing having a recessed portion and an elongated slot therethrough, and a tuck needle in said slot and projecting through said bushing and adapted to be supported in an inclined position by said bushing, said recessed portion and slot of said bushing being adapted to displace said needle transversely to a predetermined position while it is being depressed from an upwardly inclined position to a horizontal position.

23. In an apparatus for applying a wrapper to a cigar bunch, a bearing, a hollow rotatably adjustable bushing within said bearing having a recessed portion and an elongated slot therethrough, and a tuck needle in said slot and projecting through said bushing and adapted to be supported in an inclined position by said bushing, said recessed portion and slot of said bushing being adapted to displace said needle transversely to a predetermined position while it is being depressed from an upwardly inclined position to a horizontal position, said portion of said bushing operating to guide said needle transversely to a predetermined position when the needle is moved from the horizontal depressed position to an upwardly inclined position.
